UNITED STATES PATENT OFFICE

131,297

DESIGN FOR A SALAD PLATE

Inez B. Donovan, Terminal Island, Calif., assignor to Van Camp Sea Food Co. Inc., Fish Harbor, Terminal Island, Calif.

Application May 6, 1941, Serial No. 100,803

Term of patent 14 years

To all whom it may concern:

Be it known that Inez B. Donovan, a citizen of United States of America, residing at Fish Harbor, Terminal Island, county of Los Angeles, State of California, have invented a new, original, and ornamental Design for a Salad Plate, of which the following is a specification, reference being had to the accompanying drawing, forming part thereof.

Figure 1 is a top plan view, and Fig. 2 is a sectional view along lines 2—2 on Fig. 1 of a salad plate, showing my new design.

I claim:

The ornamental design for a salad plate, as shown.

INEZ B. DONOVAN.
